137 Design

(126) STOVES & FURNACES,
Heating Stoves.

James Major, Troy, N.Y.
Designs of Parlor Stove Plates.

Patented October 16, 1850.

Des 737

Dec. 737

Letters Patent. No. 737. Dated Oct 16th 1855.

The schedule referred to in these Letters Patent, and making part of the same.

To all whom it may concern,

Be it known that I, James Wagner, of Troy, in the County of Rensselaer, & State of New York, have invented or produced a certain new & useful design of parlor Stove Plates, which I call the "Prize Parlor," and I do hereby declare that the following is a full, clear, & exact description of the same; reference being had to the accompanying drawings, & to the letters of reference marked thereon, making a part of this specification, whereof

Fig. 1. is a view of the front plate, and
Fig. 2. a sectional view thereof,

Figures 3 & 4. are top & edge views of the top, plate.
Figures 5 & 6. are plan & sectional views of the end
plate,

The description of the plates is as follows, viz.:
The design of front plate Fig. 1. consists of the Gothic moulding A, at the sides, & terminating in the scrolls B.B', & shell C, at the top, D, is a shell ornament, occupying the center of the top front, & partially

2

covering a shell E, E' , upon each side of it. F, F' are shells at the top of the side panels. G, G' are sunk panels, with the moulding G G' .

The design of the top-plate Fig. 3, consists of the ornamental boiler hole H , & the shells I, I' , are arranged upon each side of it, with moulding J , around the edges. The design of the end-plate Fig. 5, consists of the Gothic circles K , and mouldings L , arranged upon the panel, & around the edges of the plate.

Having described my design of Parlor

Stove plates,

What I claim as new, & desire to secure by Letters Patent, is the ornamental design & configuration of Parlor Stove Plates, such as herein described and represented in the annexed drawings
